**COMBINED ESCUTCHEON AND FACE PLATE FOR
A TELEVISION RECEIVER CABINET**

Melvin H. Boldt, Glenview, Ill., assignor to Zenith Radio
Corporation, a corporation of Delaware

Application March 24, 1958, Serial No. 50,143

Term of patent 7 years

(Cl. D56—4)

Figure 1 is a front elevational view of a combined escutcheon and face plate for a television receiver cabinet, showing my new design, it being understood that the ornamentation partially shown at the bottom extends the full width of the design.

Figure 2 is an enlarged fragmentary cross-sectional view taken on the line 2—2 of Figure 1;

Figure 3 is an enlarged fragmentary cross-sectional view taken on the line 3—3 of Figure 1; and

Figure 4 is an enlarged fragmentary view thereof showing a portion of the ornamentation at the bottom.

The sides and top of the combined escutcheon and face plate are plain.

I claim:

The ornamental design for a combined escutcheon and face plate for a television receiver cabinet, substantially as shown and described.
